UNITED STATES PATENT OFFICE.

JOHN G. CAPSTAFF, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC-PRINTING APPARATUS.

1,306,946.

Specification of Letters Patent. Patented June 17, 1919.

Application filed November 5, 1917. Serial No. 200,409.

To all whom it may concern:

Be it known that I, JOHN G. CAPSTAFF, a subject of the King of Great Britain, residing at Rochester, in the county of Monroe and State of New York, have invented certain new and useful Improvements in Photographic-Printing Apparatus, of which the following is a full, clear, and exact specification.

10 This invention relates to photographic printing apparatus and more particularly to apparatus for printing a plurality of images in predetermined relative positions. Since the present preferred embodiment of my invention is especially adapted to print two images from opposite sides onto a photographically sensitive element, I shall describe such application of it, by way of illustration.

15 20 The chief object of my invention is to provide a simple, inexpensive printing apparatus, containing all necessary adjustments for easy and accurate work with different thicknesses and sizes of plates or other image bearing media. Other objects will herein-after appear.

In the accompanying drawing:—

Figure 1 is a perspective view of the preferred embodiment of my invention with the 30 upper plate holding member in raised position.

Fig. 2 is a longitudinal section showing the plate holding members in printing position.

35 Fig. 3 is a transverse sectional view of the lower plate holding member.

Fig. 4 is a detailed perspective view of one of the clamping blocks.

Fig. 5 is a fragmentary sectional view 40 illustrating one of the adjusted positions of the plates in their clamps.

The lower plate holding member 1 in my apparatus has mounted thereon an adjustable block 3 connected by hinges 9 to the 45 other plate holding member 2, the axes of the hinges being shown in this example as substantially parallel to the upper face of member 1. The block 3 has a large opening 41 through which passes a relatively smaller screw threaded post 4 rising from plate 5 secured in a countersunk opening in the upper face of member 1 by means of screws or other approved attaching devices 6. Resting on the top of block 3 and slidably over 55 post 4 is a clamping plate 7 which is engaged

by a wing nut 8 threaded on to post 4. Since the post 4 is considerably smaller than the opening 41, the block 3 is bodily slideable and angularly adjustable over the upper surface of member 1 when the wing nut 8 and clamping plate 7 are suitably loosened.

The members 1 and 2 are provided with rectangular openings 10 and 11 through which the printing light may enter. The transverse walls of these openings are provided with guiding grooves 12, 12, in which slide the tongues 17 of the clamping blocks 16. These clamping members 16 are provided on their rear faces with bearing members 18 against which bear the inner ends of thumb screws 19 which are operatively engaged with threaded plates 21 attached to the outer lateral faces of members 1 and 2, as indicated in Fig. 1. The inner edges of the blocks 17 are cut away and provided with metallic angle pieces 23, the vertical portions of which are adapted to engage one edge of a plate, as indicated in Fig. 3. Upon the opposing faces of the openings 10 and 11 are cut away portions bearing corresponding metallic inner pieces 22 attached by any suitable devices 27. The sides of openings 10 and 11 which are at right angles to the sides bearing metallic pieces 22 and 23, also have cut away portions in which are fitted metallic angle pieces 25, shown most clearly in Figs. 2 and 5. It is noted that the depths of the cut away portions and consequently the depths of the vertical members of pieces 22, 23 and 25 are generally greater than the thicknesses of the plates normally used in my apparatus.

Sensitized films and plates adapted to receive light-impressions or printings from the opposite sides thereof are well known to persons skilled in the art of color photography. For making two-color positives, for instance, suitable color-selection images are printed in registry from opposite sides onto such a film or plate and, after the regular coloring manipulations, a colored picture is obtained. The images printed upon the opposite sides of the film may not be necessarily adapted for registration, but may be, for instance, color-selection stereoscopic images, commonly referred to in the art as anaglyphs. Certain parts of such images should bear a definite location with respect to each other. My printing apparatus is particularly useful in making such color pic- 110

tures or such anaglyphs, and by way of example, I shall describe the operation of my apparatus, when so used.

After swinging member 2 upwardly out 5 of the way, the plate 15, with its image bearing face preferably upward, is clamped between the pieces 22 and 23 by a suitable manipulation of the thumb screw 19, as indicated in Fig. 3. It is preferable that the 10 upper face of plate 15, when in position, be flush with the upper face of member 1, and this condition may be readily secured by pressing a flat gage member on the upper face of member 1 and then holding plate 15 15 against such gage member until the rotation of screw 19 pushes clamp member 16 and pieces 23 into clamping position against the edge of plate 15. The upper face of plate 15, may also be located above the upper face 20 of member 1, as indicated in Fig. 5.

After plate 15 is thus clamped, a piece of film 26, or a sheet having approximately the same thickness as said film, is laid upon plate 15 and plate 14 is placed thereover, 25 thus bringing plates 14, 15, and film 26 into approximately the same face-to-face contact, which will exist when the printing operations take place. For approximate and quite satisfactory results the film may be omitted 30 at this stage and plate 14 placed directly on plate 15. Member 2 is now swung downwardly about hinge 9 and over plate 14 to bring the vertical clamping faces of upper pieces 22 and 23 opposite the edges of plate 35 14. By turning the upper thumb screw 19 and thereby advancing the upper clamping block 16, the plate 14 will be firmly gripped in the member 2 at the proper level for future printing operations. The adjustment 40 may be such that the inner face of plate 14 is flush with the inner face of member 2, or the inner face of plate 14 may extend below the lower face of member 2, as shown in Fig. 5.

45 The film 26 is next removed and wing nut 8 is loosened to permit block 3 to be adjusted. The operator now holds the apparatus up to a source of light and looks through alined openings 10 and 11 to view 50 the images on plates 14 and 15. If the same are not in printing position, that is, either in registry or in the proper position for making anaglyphs, the operator shifts block 3 either angularly or bodily or both in any 55 direction over the face of member 1 and thereby moves the hinge 9 together with the member 2 and its contained plate 14. Such adjustment readily allows the two images to be brought into the proper relative position. Thereupon, wing nut 8 is tightened 60 to clamp the block 3 in its adjusted position. The plates 14 and 15 have, by the above series of operations, been properly positioned so as to correctly locate their images 65 and to correctly locate their contact surfaces

to operatively engage the intervening film or plate during the subsequent printing steps.

The operator now raises member 2 and places a sensitized film or plate of the kind hereinabove mentioned between the plates 70 14 and 15 and then presses members 1 and 2 together, holding them in this position either by hand or by any suitable or ordinary clamp engaging the outer ends of members 1 and 2. This loading will, of course, 75 be done under conditions where the light reaching the film will be insufficient in quantity or color to injure it. The apparatus is now placed with first one printing window and then the other printing window toward 80 the printing light, thus printing the images successively from the plates 14 and 15 upon the opposite sides of the film 26. Obviously with suitably arranged printing lamps the light may enter both windows 10 and 11 simultaneously to make the printing operation 85 merely a single step.

While in the above example, I have referred to the image bearing media as plates, 90 I do not wish to imply that the apparatus is limited for use with ordinary photographic plates, but in the claims I have used the word "plates" generically to designate any suitable image-bearing element which may be fastened in adjusted position in my apparatus. 95

In certain cases, particularly where a relatively small piece of film is used, the inner face of either or both plates 14 and 15 may be sunk below the plane of the inner faces of 100 members 1 and 2, this being a matter of choice for the operator. It is also noted that the movable clamping members 16 permit the apparatus to accommodate plates 14 and 15, whether they fill the available space 105 in openings 10 and 11 or are smaller in area than such openings. Such plates are thus accommodated even when they are of different sizes and thicknesses.

While in the description I have referred 110 to parts of my apparatus as upper or lower, such terms are merely used for convenience in explaining the relation of the parts as shown in the drawing. The apparatus being portable, may be loaded and printed in 115 any preferred position.

Having thus described my invention, what I claim and desire to secure by Letters Patent of the United States, is:

1. In photographic printing apparatus, a 120 set of plate-holding members arranged to move into and out of printing position, and a device for adjustably predetermining the relative location of said members when in said printing position.

2. In photographic printing apparatus, a 125 set of members, each provided with plate-holding means, said members being movably connected to bring said plates into and out of printing position, and means for selec- 130

tively determining the positional relation which said plates bear with respect to each other when in said printing position.

3. In photographic printing apparatus, a pair of members, each provided with a plate-holding device, and connections between said members including a pivot and means for adjusting said pivot.

4. In photographic printing apparatus, a pair of plate-holding members, and connections between them including a hinge connected with one of said members with its axis substantially parallel with the other member, and means for adjusting the position of the hinge with relation to said other member.

5. In photographic printing apparatus, a pair of plate-holding members, a block movably carrying one of said members and adjustable both angularly and slidably on the other member, and means for retaining said block in adjusted position.

6. In photographic printing apparatus, a plate-holding member having a post thereon, a block on said member having an opening receiving said post but of greater size than the post to permit the block to turn angularly on the member and to slide bodily in any direction on said member, a clamping nut on said post, a clamping plate resting on the block and engaged by the nut, and a second plate-holding member, the operative position of which is controlled by said block.

35 7. In photographic printing apparatus, a plate-holding member, a device adjustably mounted to move thereon and approximately parallel therewith, and a second plate-holding member the operative position of which, relative to the first named member is controlled by said device.

8. In photographic apparatus for print-

ing from opposite sides onto a sensitive element, a plate-holding member and a second plate-holding member, between which and the first named member the element is adapted to be located during printing, said second member being mounted on the first named member to move toward and away from the upper face of the first named member and being adjustable angularly and bodily in any direction parallel to said face.

9. In photographic printing apparatus, a member having plate-holding means thereon, a second plate-holding member having means for holding a plate in predetermined position by adjustably engaging edges thereof, and pivotally and slidably adjustable connections between said members.

10. In photographic apparatus for printing from opposite sides onto a sensitive element, a pair of members connected to move into and out of printing position with said element between them, said members having plate clamps adjustable thereon, the opposing faces of which adjustably engage the edges of plates, said faces of the clamps being of greater depth than the thickness of a normal plate, and means for adjustably determining the relative locations which said members occupy when in printing position.

11. In photographic printing apparatus, a pair of members, each having means for adjustably holding plates of different sizes and thicknesses, and a device for adjustably predetermining the relative location of said plates for printing.

In testimony whereof, I have signed this specification in the presence of two witnesses this 1st day of Nov., 1917.

JOHN G. CAPSTAFF.
